MACHINE FOR DRESSING EDGES OF METAL SHEETS AND THE LIKE

William F. Spahr, New Orleans, La.

Application January 2, 1943, Serial No. 471,198

7 Claims. (Cl. 51-128)

This invention relates to grinding or cleaning machines for sheet metal and analogous material, and particularly to grinding machines for cleaning or conditioning the edges of metal sheets preparatory to the welding operation.

In grinding or cleaning the edges of sheet metal for certain types of welding machines, as for example a so-called stitch welder, it is desirable that the edge be ground evenly and thoroughly without burning the metal. Since the edge to be ground is usually relatively thin and the sheet is naturally flexible, the problem becomes more difficult than where relatively thick and more or less rigid material is involved.

An object of the present invention is to provide a grinding or cleaning machine for sheet metal to place the same in condition for welding which will function to produce a thoroughly cleaned or ground edge devoid of low spots or pits and without burning the sheet, and which at the same time is of relatively simple construction and easy to operate.

Another object is to provide a machine of the type specified which will perform its work accurately with a minimum of manual attention and at the same time be capable of producing at maximum speed without sacrificing in any manner the quality of the work.

A further object is to generally improve and simplify machines of this type.

The foregoing and other objects and advantages of my improved grinding and cleaning machine will become apparent in view of the following description taken in conjunction with the drawings, wherein:

Fig. 1 is a view in front elevation of a machine in accordance with the invention;

Fig. 2, a plan view of Fig. 1;

Fig. 3, a section taken on the line 3-3 of Fig. 2;

Fig. 4, a detailed perspective of the mounting assembly for the grinding head or wheel;

Fig. 5, a transverse vertical section through the grinding head; and

Fig. 6, a fragmentary sectional view taken substantially on the line 6-6, Fig. 2.

Referring to the drawings in detail, the machine comprises a table 10 which is supported by suitable framework including vertical legs 11 and horizontal cross members 11a and 11b. The table is preferably formed with a central recess or well 12 permitting an attendant or attendants to more readily handle the sheets which are fed to the machine. The opposite side edges of the table are provided with en-

trance guides 13 and 13' and additional final guides and wear strips 14, 14' and which latter guides determine the position of the edge of the sheet as it is engaged by the grinding wheel.

The machine herein disclosed has two grinding units, one at each side of the table 10, and since these machines are of similar construction, a description of one will suffice for both.

Each edge grinding or cleaning unit comprises a grinding head or stone 15, note particularly Fig. 5, which is of deeply dished or cup-shaped contour, the peripheral vertical wall of the head or stone being of substantially uniform thickness from its lower edge to the point where it merges with the upper horizontal wall of the stone. Thus, the stone will grind a definite area or edge portion of the sheet as the grinding edge wears down. Also, this construction of the head tends towards maximum life with a minimum amount of material, the head being adjustable vertically and also arcuately, as will be presently described.

The grinding head or stone 15 is secured on the lower end of a shaft 16 by means of a backing member 17 and nut 18. The shaft 16 is rotatably mounted in bearings 19 and 19' secured to T-shaped brackets 20, note particularly Fig. 4, which are formed on the outer edge of a vertical flange projecting outwardly from a bolting-on plate 20', the latter being secured on the upper portion of a plate-shaped bracket 21 which also has mounted thereon a driving motor 22. The drive is transmitted from the motor to the grinding head through a pulley 23 secured on the upper end of the armature shaft 24 of the motor, the said pulley being of the double grooved type and having trained thereover V-belts 25 which are also trained over a pulley 26 secured on the upper extremity of the shaft 16.

The bracket 21 which carries the driving motor 22 and grinding head 15 is mounted for vertical adjustment on a main supporting bracket 27, the latter being formed with a dovetail guide boss 27' and the plate 21 being formed with a dove-tail groove or guideway slidably receiving said boss, note particularly Figs. 2 and 4; the said bracket 27 in turn being mounted for arcuate adjustment on a web 28' projecting outwardly from a main supporting bracket 28 in a manner to be more fully described.

The upper edge portion of the plate 21 and the guide boss 27' are respectively formed with bearing lugs 29 and 30 through which a screw threaded shaft 31 projects and has secured on

the upper end thereof a hand wheel 32. By rotating the hand wheel 32, the plate 21 together with the grinding head 15 and driving motor 22 may be adjusted vertically on the plate 27.

To provide for an arcuate adjustment of the grinding head 15, the web 28' of the main supporting bracket 28 is provided with a stud 33 which projects through a bearing hole formed in the lower extremity of the bracket 27. Plate 27 is formed with a pair of arcuate slots 34, as best shown in Figs. 1 and 4, adapted to receive bolts 35 projecting from the web 28'. The plate 27 is formed with an additional arcuate slot 36 through which an abutment 37 formed on the web 28' projects. Screw threaded lugs 38 are also formed on the plate 27 and are adapted to receive adjusting screws 39 which are adjustable against the abutment 37 and whereby bracket 27 together with the plate 21 and parts carried thereby may be adjusted arcuately as desired.

It will thus be seen that the grinding stone 15 may be adjusted vertically by hand wheel 32 to compensate for wear and to also accurately position the stone with respect to the sheet to be ground, and the stone may also be tilted or adjusted arcuately by means of screws 39 not only to compensate for wear but to also definitely locate the grinding edge of the stone with respect to the edge of the sheet.

A pressure pad or anvil 40 is disposed between the guide members 14, note particularly Fig. 6, said pad being secured on the upper end of a plunger 41 slidably mounted in a housing 42 against the resistance of a spring 43. An adjusting screw 44 is threaded in the lower end of the housing 42 and is adapted to abut the spring 43 and whereby the vertical position and also to some extent the cushioning action of the pad may be adjusted with respect to the stone 15. The tension of the springs 43 should be such as to offer enough resistance to depression of the anvil to ensure a thorough grind without burning the metal, and if properly selected, should need no adjustment as to tension. This pressure pad or anvil in conjunction with the vertically and arcuately adjusted grinding head or stone 15 insures a ground surface of smooth and uniform contour devoid of pits or unground portions and with a minimum of manual attention.

To facilitate handling of the sheets, rolls 45 and 45' are shown mounted on the front edge of the table 10, said rolls being carried by bearing brackets 46 and 46'.

From the foregoing, the operation of the machine will be readily understood. One or more operators stand in the well or recess 12 of the table 10 and feed sheets to the machine, the sheets being guided by the preliminary guides 13, 13' and definitely located by the final guides 14, 14'. As the edge of each sheet moves over the pressure pad or anvil 40, it comes in contact with the lower edge of the grinding stone 15, the screws 39 being adjusted to obtain the proper angle of grind while the hand wheel 32 being adjusted to locate the vertical position of the head with respect to the sheet. In actual practice, the pressure pad 40 is adjusted to a point where it is slightly above the wear strip portions of the guides 14, 14'. A sample piece of metal may first be inserted between the grinding wheel and anvil or pressure pad to gauge the exact arc of contact of the grinding wheel, which may be obtained by adjusting the screws 39. The sample is then removed and the stone is adjusted vertically by

means of the hand wheel 32 until its grinding surface is just clear of the pressure pad or anvil, whereupon the said wheel 32 is locked in position and the machine is ready to receive sheets to be ground. Sheets for which the machine is primarily adapted have the edges ground on one side only, as in the manufacture of metal barrels or drums. The machine has demonstrated its ability to grind the edges of sheets smoothly, accurately and evenly without burning or otherwise damaging the metal; it is of relatively simple construction and will operate indefinitely with a minimum of manual attention. When the grinding stone wears to the extreme upper portion thereof, the same may be tilted to a point where it will still carry on its grinding function until it wears through the upper wall.

It will be understood that the foregoing and other important advantages are inherent in the machine, and that certain variations in construction and design of parts may be adopted to obtain these advantages without departing from the spirit or scope of the invention as defined by the appended claims.

What is claimed is:

1. A machine for grinding the edges of metal sheets to condition the latter preparatory to welding or like operations, comprising a table, a substantially vertically disposed, cup-shaped grinding stone located adjacent one side of the table, guides connected to the table for grinding the sheets along the latter beneath the stone, said guides being interrupted adjacent the stone to provide a space in which the stone rotates, an anvil disposed in said space beneath the stone, a plunger supporting said anvil, a housing having a bore receiving said plunger, a spring disposed in said bore for resiliently supporting the plunger and the anvil carried thereby, means for adjusting the tension of the spring to thereby adjust the vertical position of the anvil, a motor for driving the stone, a bracket on which said stone and motor are mounted, another bracket on which said first named bracket is mounted for vertical sliding movement, means for adjusting said first named bracket on said second named bracket to thereby adjust the vertical position of the stone with respect to the sheet to be ground, a support for said second named bracket, means connecting said support to the table, means mounting said second named bracket for arcuate adjustment on its support and whereby the grinding stone may be adjusted arcuately in connection with its vertical adjustment to definitely position the stone with respect to the edge of the sheet and to also compensate for wear on the stone.

2. A machine for grinding the edges of metal sheets to condition the latter for welding or like operations comprising a table, a grinding head of hollow cup-shaped form disposed above and at one side of the table and slightly overlapping the edge of the table, guide members connected to the edge of the table for guiding the sheets therealong beneath said stone, said guide members being interrupted adjacent the stone to provide a space beneath said stone, a resiliently mounted anvil or pressure pad mounted in said space, a bracket rotatably supporting said grinding stone, a motor having driving connection with said stone, said motor being also carried by said bracket, another bracket supporting said first-named bracket for vertical sliding adjustment, said table being provided with outwardly projecting support and said second-named bracket being mounted for arcuate adjustment on said latter support.

and whereby the grinding head may be tilted or adjusted arcuately with respect to the edge to be ground and at the same time be adjusted vertically with respect to said edge.

3. A machine for grinding the edges of metal sheets to condition the latter for welding and like operations, comprising a table having combined guides and wear strips connected to a side edge thereof, said guides and wear strips being interrupted along their length to provide a grinding space, a pressure pad mounted for limited vertical movement in said space, means cushioning the action of said pressure pad, a grinding stone of deeply-dished cup-shaped contour disposed above said pad, a substantially vertically disposed shaft mounting said stone, a bracket member rotatably supporting said shaft, a motor for driving said stone, and means mounting said stone and motor for vertical and arcuate adjustment as a unit with respect to said pad.

4. A machine for grinding the edges of metal sheets to condition the same preparatory to welding and like operations, comprising means providing a supporting surface for the sheets to be ground, a substantially cup-shaped grinding stone disposed at least in part above said surface, a shaft mounting said stone, means for rotating said shaft, guide members connected to said surface, said guide members being interrupted to provide a space beneath said stone, a resiliently mounted pressure pad located in said space, bearing means for said shaft mounted for vertical adjustment to thereby adjust the vertical operating position of the stone with respect to the sheet to be ground, and means supporting said bearing means from said table for arcuate movement with respect to the latter and whereby the angular position of the stone may be adjusted with respect to said sheet.

5. A machine for dressing the edges of metal sheets preparatory to welding and like operations, comprising a table having an open recess therein to accommodate one or more operators, sheet

guides connected to and projecting upwardly from the table, a hollow cup-shaped grinding stone, a substantially vertically extending shaft supporting said stone for rotary movement above said surface, a spring-mounted pressure pad disposed beneath said stone, means for adjusting the position of said pad with respect to said stone, a motor for driving said shaft, a vertically slideable member supporting said motor and grinding stone, another member providing a support for said first-named member, an adjusting screw connecting said first-named member to said second-named member for determining the vertical position of the stone, and means connecting said second-named member to said table for arcuate adjustment.

6. In a machine for grinding the edges of metal sheets to condition the latter preparatory to welding and like operations, means providing a supporting surface for the sheets, said means having one or more recesses to accommodate one or more operators a resiliently mounted anvil located adjacent said surface and beneath the plane of travel of the sheets, a radially faced grinding stone disposed over said supporting surface means, and means for adjusting the vertical and arcuate position of said stone with respect to said support.

7. A machine for grinding the edges of metal sheets to condition the latter for welding and like operations, comprising a support for work having one or more recesses to accommodate one or more operators, a pressure pad associated with said support and mounted for limited vertical movement, means cushioning the action of said pressure pad, a radially faced grinding stone disposed above said pad, a substantially vertically disposed shaft mounting said stone, a bracket member rotatably supporting said shaft, a motor for driving said stone, and means mounting said stone and motor for vertical and arcuate adjustment as a unit with respect to said support.

WILLIAM F. SPAHR.
